R. K. PAYNE.
SAFETY ATTACHMENT FOR RAILROAD SPEEDERS.
APPLICATION FILED NOV. 17, 1914.

1,134,410.

Patented Apr. 6, 1915.

UNITED STATES PATENT OFFICE.

ROY KRATER PAYNE, OF BEAVERTON, OREGON.

SAFETY ATTACHMENT FOR RAILROAD-SPEEDERS.

1,134,410.

Specification of Letters Patent.

Patented Apr. 6, 1915.

Application filed November 17, 1914. Serial No. 872,553.

To all whom it may concern:

Be it known that I, ROY KRATER PAYNE, residing at Beaverton, in the county of Washington and State of Oregon, have invented new and Improved Safety Attachments for Railroad-Speeders, of which the following is a specification.

My invention has for its object to provide a simple and effective means adapted for being readily applied to railroad speeders, either of the motor driven or hand car type having three or four wheels, and it has for its object to provide a means of the character stated, of a simple and inexpensive construction that serves to catch the speeder car as it leaves the rails and supports it for gliding along the rails so that the said car may be quickly stopped without perceptible jars and without injury to the operator or the car.

With other objects in view that will hereinafter appear, my invention embodies certain novel features of construction, and peculiar combination of parts, all of which will be hereinafter fully explained, specifically pointed out in the appended claims and illustrated in the accompanying drawing, in which:—

Figure 1 is a perspective view of my invention, so much of a motor driven speeder being shown as is necessary to illustrate the practical application of my said invention, the speeder car being shown as traveling on the rails. Fig. 2 is a similar view, the "speeder" or car being shown off the track and supported on the rails by my improved attachments or safety devices. Fig. 3 is a perspective view of the safety guard or appliance for one of the large wheels. Fig. 4 is a transverse section thereof on the line 4—4 on Fig. 3. Fig. 5 is a perspective view of the guard or safety device for one of the small wheels. Fig. 6 is a transverse section thereof on the line 6—6 on Fig. 5.

In the practical application of my invention, the same, when the car to which it is applied has four wheels, as shown in the drawing, consists of four guards or safety attachments, one for each wheel, two of which, those for the large or heavy side wheels, including bearing bars that extend across the front face of the wheel and beyond the opposite sides thereof, the purpose of which will presently appear.

Each of the guard devices referred to in-

cludes a heavy bearing or cross bar 1, provided with a longitudinal slot 10, that forms a seat for a solid roller 2, held up against the under side of the bar 1 by clip members 3—3 as is clearly shown in Fig. 4, and the said cross bar 1, is fixedly attached to a hanger frame 4 consisting of pendent side arms 40, a bottom cross member 41 and an upper tubular cross member 42, as is clearly shown in Fig. 3, which illustrates the bearing bar 1 secured to the cross member 41 of the said frame 4. A frame 4 is suspended across the front end of each of the larger wheels at the heavy side of the car and in any suitable manner, preferably by having the tubular bar 42 engage with a arm 43, fixedly attached to the car framing and the cross or bearing bars 1 are of such length that their opposite ends project beyond the opposite faces of the wheels, so that should one or both of the wheels jump the track at either side of the rail, ample provision is made for projecting the bar 1 to drop onto the rail. To take up the impact on the said guards, brace members 7 are attached to the side arms 40, extend rearwardly and are fixedly connected to the pendent members 80 of the parallelly disposed frame beams 8 on which the carriage and motor mechanism for the speeder car are supported and between which the mud guards 9 for the large wheels are secured as shown.

The guards for the smaller wheels are each constructed as shown in Figs. 5 and 6 by reference to which it will be noticed the same includes a Ω shaped frame 11, the inner one 12^a, of the pendent or hanger arms of which, is larger than the other arm 12, the reason for which will presently appear. The frame 11 is pendently supported from the cross or axle beam 14 of the car frame and it supports a cross rod 15 upon which is mounted a tubular roller 16 as shown.

From the foregoing description taken in connection with the drawing, the complete construction, the advantages of my invention will be readily apparent.

By reason of providing each of the large wheels with a guard device, as shown, it follows that should either of said large wheels jump the track, in either direction, the cross bar with the solid roller will drop down onto the track, and form a roller bearing for taking up the weight of that side of the car

as the same slides along, during the operation of stopping the car, it being understood that should the car wheels, at the heavy side jump inside of the rail, as indicated in Fig. 5 2, the guards therefor instantly drop onto the rail, while the roller bearings or the cross bars of the guard devices for the smaller wheels likewise drop onto the other rail and since the supports for the car are 10 now in the nature of rollers, the momentum of the car tends to absorb the heavy shocks or jars and at the same time provide for quickly bringing the car to a stop as it thus glides along the rails with the flanges of 15 the several wheels high enough to miss the ground and the ties. By extending the inner one of the hanger arms of the guards for the wheels at the light side of the car below the roller, danger of the car moving 20 laterally to such distance that the roller supports will move off the rails is prevented the said extended end acting as a stop member for engaging the rail. Furthermore, since the car, when the wheels leave the track 25 glides along the track, it is kept from stopping too suddenly and in case it jumps on the side of the small wheels, the guards keep the said wheels and also the large wheels from dropping between the ties and when 30 the car jumps the other way the guards on the heavy side catch the heavy part of the car and the light wheels run on the ballast between the ties. The guards for the large wheels have the ends of the cross bar 1 35 turned down to form flanges to keep the car straight on the rails after jumping the track.

What I claim is:—

1. In a speeder car, the combination with the truck, of guard members, one for each 40 wheel at one side of the truck, the said guard members each including a supporting member that extends across the adjacent rail, and an auxiliary guard member for each wheel on the other side of the truck and located at the inner side of the said wheels only.
2. As an improvement in speeder cars, the combination with the truck frame, said

frame including arms that extend across the wheels at one side, means for bracing the 50 outer ends of said arms to the car framing, hangers pendently supported on the inner ends of each of the said arms, a cross member on the lower ends of each of the hangers located adjacent the wheels to drop onto the 55 rail when the said wheels leave the track and having stop portions at the ends for engaging the rail from either side, and an auxiliary guard member for each wheel on the other side, said auxiliary guard members 60 being pendently supported from the truck frame at the inner side of their respective wheels, the said auxiliary guard members including a cross member for riding on the rail when the adjacent wheels jump outside 65 of the rail engaged thereby, the said auxiliary guard members also including a stop portion for engaging the inner edge of the adjacent rail only.

3. In a speeder car, the combination with 70 the truck frame; of a guard member, one for each wheel at one side of the said truck, the said guard members each including a hanger pendently supported from the truck frame, a cross bar on the lower end of the 75 hanger that extends across the rail and beyond the opposite sides of the wheel, a roller bearing mounted on the under side of the said cross bar, the ends of the said cross bar being bent down to form stops for 80 engaging the rail, and an auxiliary guard member for each wheel on the other side of the truck, located at the inside of the said wheel, said auxiliary guards each including a Ω-shaped hanger pendent from the truck 85 frame and located at the inner side of the said last mentioned wheels, a roller between the pendent arms of the said hanger the inner one of the said arms being extended below the roller to form a stop for engaging 90 the inner side of the adjacent rail.

ROY KRATER PAYNE.
